A. A. THOMAS

ELECTRIC PHONOGRAPH REPRODUCER

Filed Dec. 30, 1925

Patented Sept. 7, 1926.

1,598,895

UNITED STATES PATENT OFFICE.

ADOLPH A. THOMAS, OF NEW YORK, N. Y.

ELECTRIC PHONOGRAPH REPRODUCER.

Application filed December 30, 1925. Serial No. 78,277.

This invention relates to devices for electrically reproducing sound, and its object is to provide new and improved electromagnetic reproducing mechanism controlled by a needle or stylus arranged to be mechanically actuated by a medium of recorded sound, such as a phonograph record and the like. My new instrument is characterized by the absence of a diaphragm, by a vibratory unit of such low inertia and high efficiency as to reproduce the most delicately recorded sound, and by a construction of utmost simplicity.

In phonograph records heretofore made, the spiral track usually has about 80-100 lines to the inch, and a 12-inch record plays about five minutes. By means of improved recording methods it has been proposed to make records with several hundred lines to the inch, so that a single record will play for half an hour and longer. Now, with such finely cut record grooves, the use of a mechanical reproducer is out of the question. The high inertia of the stiff diaphragm would be too much for the delicate vibrations of the needle and would be liable to break down the frail walls of adjacent grooves. The same objection applies to a reproducer of the microphone type, where a diaphragm operates against packed resistance granules.

In the electric reproducer of my invention, the vibratory unit actuated by the needle is so light as to have no appreciable inertia, and its vibrations are not damped or impeded by any magnetic drag of the electromagnetic mechanism. As a result, the vibratory unit responds freely and faithfully to the minutest vibrations produced on the needle by the record groove. To this end, I mount on the free end of the needle arm a freely movable coil arranged to vibrate in a magnetic airgap to cut the lines of force. The vibrations of the coil thus generate an electric current, which is amplified by any suitable means to operate a loud-speaker or other telephone receiving device. The mounting of the coil is such that the vibrations at the needle point are transmitted to the coil in greatly amplified ratio, so that the smallest movement of the needle produces sufficient movement of the coil to generate a current in its circuit. The entire mechanism is exceedingly simple and may be housed in a little casing properly

mounted to allow the needle to travel over the record.

In order to explain my invention so that those skilled in the art may understand and use the same, I have selected two illustrative embodiments as shown in the accompanying drawings, which I shall now describe in detail. In these drawings—

Fig. 1 is a face view of an electric reproducer constructed in accordance with my invention, the cover of the casing being removed to show the interior;

Fig. 2 is a cross-section approximately on the broken line 2—2 of Fig. 1;

Fig. 3 is a plan view in section on line 3—3 of Fig. 1, showing the arrangement of springs for normally centralizing the needle arm;

Fig. 4 is a detached sectional view on an enlarged scale to show the mounting of the vibratory coil on the free end of the needle arm;

Fig. 5 represents diagrammatically the various positions of the coil with respect to the pole pieces of the magnet;

Fig. 6 shows an interior face view of a modified form of reproducer embodying my invention;

Fig. 7 is a cross-sectional view approximately on the broken line 7—7 of Fig. 6;

Fig. 8 is a fragmentary view, on a greatly exaggerated scale, taken approximately on the broken line 8—8 of Fig. 7 to show the construction of the front spring for the needle arm; and

Fig. 9 is an enlarged fragmentary view on line 9—9 of Fig. 7, showing the rear spring for the needle arm.

Before taking up these drawings in detail, let me explain that the parts are purposely shown in exaggerated dimensions, so as to make the figures as clear as possible. The actual construction of the reproducer is considerably more compact than shown in the drawings.

Referring first to the embodiment illustrated in Figs. 1-4, there is a suitable casing indicated as a whole by C for housing the different parts of the reproducer. The casing C is here shown circular in form, consisting of a back plate 1, a cylindrical body section 2 and a removable front plate 3. The back plate 1 is provided with a hub 4, by means of which the reproducer is removably mounted on a suitable supporting arm 116

5, which allows the instrument to travel over a record. The casing C is preferably formed of thin light metal, such as aluminum, or an aluminum alloy, which is sufficiently rigid and is non-magnetic. If desired, however, the casing may be shaped or molded out of suitable insulating material, such as bakelite or other composition having the requisite strength.

19 A needle arm 6 is pivoted to casing C in any suitable way. In the present instance, I have shown the casing provided with a pair of lugs 7, in which are mounted adjustable bearing screws 8 having pointed ends 15 for pivotally supporting the needle arm. The outer end of needle arm 6 is in the form of a needle holder 9. In the broader aspect of my invention, the needle holder need not be a direct or integral part of the needle 20 arm, for these two parts may be separately mounted and properly connected for simultaneous operation.

Within the casing C is mounted a permanent magnet indicated as a whole by M. 25 For convenience I have shown the magnet mounted on the back wall of the casing and secured in position by screws 10 or otherwise. The magnet M is preferably circular, following closely the outline of the cylindrical body section 2 of the casing, whereby a magnet of maximum length is obtained. The magnet terminates in a pair of projections 11, extending forwardly of the casing. These projections may be formed integral 30 with the body of the magnet. To the projections 11 are secured pole pieces 12 of soft iron, or of any suitable alloy having high magnetic permeability. The pole pieces 12, which are cylindrical in this case, are arranged in axial alignment to provide an air-gap 13, in which vibrates a coil 14 suitably mounted on the inner end of the needle arm 6. In the drawings I have shown the needle arm terminating in a rearwardly projecting lug 15, to which is clamped a band 16 by means of a screw or rivet 17. The band 16, which may simply be a strip of any suitable material, tightly surrounds the coil 14 and holds the same rigidly attached to 40 the needle arm. The ends 18 of the coil are connected to a pair of binding posts 19 mounted on the rear wall 1 of the casing. Conductors 20 lead from the binding posts 19 to suitable apparatus for amplifying the 45 currents generated in coil 14 during the vibrations of the needle arm 6. If the supporting arm 5 for the reproducer is a hollow tube, as shown in Fig. 2, the connecting wires 20 may be housed invisibly in this 50 tube, thereby adding to the neatness of the machine in which the reproducer is mounted.

Suitable spring means is provided to hold the needle arm 6 normally in predetermined position. In Fig. 2, I have shown a pair of 60 spring-pressed balls 21 arranged to engage

the needle arm on opposite sides in the plane of its vibrations. The balls 21 are mounted in small cylindrical housings 22 and 23, and are pushed against the needle arm by coil springs 24. The normal tension of these 70 springs is adjustable by means of screws 25. The back wall of the casing may be provided with a hole 26 in alignment with screw 25, so as to permit the insertion of an instrument for adjusting the screw. The front 75 spring housing 22 is carried by (or forms part of) a bracket 27, as best shown in Fig. 3. The bracket 27 is secured by screws 28 to a pair of lugs 29 projecting upwardly 80 from the bottom of the casing. The lugs 29 are connected at the upper end by a cross-piece 30, which carries the rear spring housing 23. It will be understood that the spring housings 22 and 23 are sufficiently spaced at their inner ends to allow for the 85 maximum vibrations of the needle arm at that point.

The springs 25 are adjusted to give the coil 14 a normal position with respect to the magnetic pole pieces 12. In Fig. 2, the normal position of the needle arm 6 is such that the axis of the cylindrical coil 14 is substantially coincident with the axis of the cylindrical pole pieces. This means that normally the maximum magnetic flux passes 90 through the coil 12. During the vibrations of the needle arm 6 by means of a needle playing a record, the number of magnetic lines of force passing through coil 14 is varied in accordance with the amplitude of 95 vibrations of the needle arm. The variable currents thus generated in the coil 14 are passed through a suitable amplifying device which operates or controls a telephone receiver acoustically connected with a horn or 100 other sound-amplifying device.

It will be clear from Fig. 2 that the vibrations at the needle point are considerably amplified in being transmitted to the current-generating coil 14. Consequently, 110 the minutest vibrations of the needle produce sufficient movement of coil 14 to generate an electric current of variable impulses. While these impulses are very weak, there 115 is no difficulty in properly amplifying them for loudspeaking reproduction. As these amplifying arrangements are well understood by those skilled in the art, I need not show or describe them, particularly since 120 my invention has nothing to do with such accessories.

The normal position of coil 14 with respect to the magnetic poles 12, or the air-gap 13, may be other than that shown in Fig. 2. For example, in Fig. 5 the dotted circle 14^a represents the normal position of the coil 14, and the dotted circle 14^b is intended to indicate roughly the extreme position of the coil 14 to one side of its normal or central position. The other extreme po- 125 130

sition of the coil may be considered to be the same as the position of the pole piece 12 in Fig. 5. When the coil moves toward the pole pieces, the magnetic flux passing through the coil is increased. Conversely, when the coil moves out of the airgap toward the position 14^b, the magnetic flux passing through the coil is decreased. It will, of course, be understood that the 10 various positions of the coil 14 in Fig. 5 are indicated merely in a diagrammatic way, and are considerably exaggerated. In actual practice, the maximum amplitude of vibration of coil 14 will be very small.

15 The coil 14 may be made exceedingly light, so as to add very little weight and resistance to the needle arm 6. To that end, the coil is preferably wound on a cylindrical core 31 of very light material, such as paper, fiber, 20 bakelite and the like. The shell 31 had better be made of non-metallic material, so as to avoid induced currents therein which might have a disturbing effect.

25 The needle arm 6 with its needle holder 9 can be made of light, strong material, such as aluminum, so that the inertia of the vibratory arm and coil 14 may be reduced to a practical minimum. The springs 24 should be just strong enough 30 to hold the needle arm and coil 14 in normal position and to offer the proper amount of resistance to the vibrations produced by the needle. This produces a vibratory unit which as a whole possesses minimum inertia and 35 correctly responds to the most delicate vibrations of the needle. Consequently, my new instrument is particularly adapted for playing records in which the spiral track consists of many more lines to the inch than in 40 previous phonograph records that were mechanically reproduced by diaphragms.

45 In the exemplification shown in Figs. 6-8, there is a casing C' substantially rectangular in shape. Otherwise, what has been said about the construction and mounting of casing C may be considered applicable to casing C'. A needle arm 32 is pivoted to casing C' by means of adjustable bearings 33, or in 50 any other practical way. A magnet M' is firmly mounted within the casing, as by means of screws 34 which secure the magnet against the back wall of the casing. As shown in Fig. 6, the magnet is substantially 55 rectangular and closely follows the outline of the casing, so as to provide a magnetic path of maximum length in a small space. Since the body of the magnet is flat, it may be stamped out of magnet steel, either solid or laminated. The magnet M' comprises a pair 60 of outer limbs 35 and a middle limb 36. The outer limbs 35 are of the same polarity and are connected by a magnetic cross-piece 37, which is shaped at the center into a ring 38. The cross-piece 37 is made of soft iron and 65 is rigidly connected to the limbs 35 by suit-

able fastening means, such as screws 39 or otherwise. The central limb 36 is of opposite polarity from that of the outer limbs 35 and is at its free end provided with a soft iron pole piece 40 which projects into the 70 polar ring 38. The pole piece 40 is cylindrical in shape and is arranged coaxially with the ring 38, so as to provide an annular airgap 41 of substantially uniform width. As shown in Fig. 7, the polar ring 38, which 75 may be considered as one of the magnetic pole pieces, is offset with respect to the flat body of the magnet, so as to prevent short-circuiting of the flux across the central limb 36. Since the parts 38 and 40 constitute the 80 two pole pieces of the magnet, the flux will traverse the annular airgap 41 all around.

To the free or inner end of the needle arm 32 is attached a cylindrical coil 42, which is arranged coaxially in the airgap 41, so as to 85 vibrate therein. In the present instance the coil 42 is shown mounted on a cup 43 of light thin material, preferably non-metallic, such as bakelite, fiber, stiff paper and the like. The cup 43 is fastened to the needle arm 32 by 90 means of one or more lugs 44 struck up at the inner end of the needle arm so as to lie flat against the end of the cup. The front wall of cup 43 is preferably in skeleton form, or may be provided with air holes 45, so as 95 to prevent the forming of air cushions during the vibrations of the coil. Any other practical means may be used for securely attaching the coil 42 to the free end of the 100 needle arm.

Suitable spring means is employed to hold the current-generating coil 42 in normal position in the annular airgap 41, as indicated in Fig. 7. In the present modification I have shown a pair of springs 46 and 47 arranged 105 in the casing so as to engage the needle arm 32 at opposite sides in the plane of its vibration. The front spring 46 is mounted on a pair of lugs 48 to which it is secured by 110 screws 49, as shown in Fig. 8. A set-screw 115 50 adjusts the normal pressure of spring 46 against the needle arm. The adjusting screw 50 is mounted in a plate 51, which is secured to the lugs 48 by the screws 49. As shown in 120 Fig. 8, the spring 46 is formed at its lower 125 end with integral side flanges 46' and these flanges are held rigidly clamped between the supporting lugs 48 and the plate 51. The rear spring 47 is mounted on a lug 52, which 130 may be struck up from the body of the casing, thereby providing at the same time a slot 53 through which the needle arm 32 extends into the casing. The spring 47 is secured at its lower end to the lug 52 by screws 54, a retaining plate 55 being interposed. 135 The plate 55 carries a screw 56 for adjusting the normal tension of spring 47. It goes without saying that the rear spring 47 is adjusted before the central section of the casing is connected to the rear wall thereof. 140

On the back wall of casing C' are mounted insulated binding posts 57, to which are connected the leading-out wires 58 of the coil 42. Conductors 59 lead from the binding posts 57 to suitable circuit connections for including the coil 42 operatively in circuit. What has been previously said concerning the operation of coil 14 and the amplification of the currents generated thereby, is fully applicable to coil 42 without repetition.

Although I have shown and described two specific constructions of my invention, I want it understood that I have done so merely by way of example and not as a restriction or limitation. It is evident that the basic features of my invention can be mechanically embodied in various other modifications.

When I refer to my invention as a phonograph reproducer, I use the word "phonograph" in its broadest possible sense of "recorded sound." The particular type or name of sound-reproducing machine in which my invention is embodied, is immaterial.

What I claim as my invention is:

1. In an electric phonograph reproducer, a vibratory lever pivotally mounted so as to be actuated by the vibrations of a record needle and having a free inner end, a magnet having an airgap, and a coil mounted on the free end of said lever so as to vibrate in said airgap to cut the magnetic flux.

2. An electric phonograph reproducer having a magnet, and a vibratory needle arm pivotally mounted and carrying at its free end a current-generating coil arranged to vibrate relatively to said magnet in amplified ratio to the needle vibrations.

3. In an electric sound reproducer, a magnet having an airgap, a vibratory lever pivoted near one end thereof so as to provide a short arm and a long arm, acoustic means for mechanically vibrating the short arm, and a freely movable coil mounted on the free end of said long arm and arranged to vibrate in said airgap to cut the magnetic flux.

4. In an electric sound reproducer, a casing, a magnet mounted in said casing and provided with a pair of pole pieces arranged in axial alignment to provide an airgap, a vibratory lever pivoted near one end thereof so as to provide a short arm and a long arm, said lever being mounted to vibrate transversely of said casing, acoustic means for mechanically vibrating the short arm, a coil mounted on the free end of said long arm in a position to vibrate across said airgap transversely of said casing, and non-acoustic resilient means for normally holding said coil in said airgap in substantially axial alignment with said pole pieces.

5. An electric phonograph reproducer comprising a casing, a needle arm pivoted to the lower portion of said casing, the pivot point of said arm dividing the same into a short outer section and a long inner section, a magnet mounted in said casing and having an airgap near the upper end of the casing, a coil mounted on the free end of said long section of the needle arm and arranged to vibrate in said airgap in amplified ratio to the needle vibrations, and non-acoustic resilient means for normally holding said needle arm and said coil in predetermined position.

6. In an electric phonograph reproducer, a casing provided at its lower end with a pivoted needle holder, a vibratory arm arranged within said casing and connected at one end to said needle holder, a magnet so mounted in said casing that the magnetic airgap is near the upper end of the casing diametrically opposite said needle holder, and a coil carried by the free end of said arm and arranged to vibrate in said airgap transversely of the casing to cut the magnetic flux, the length of said arm being such that the needle vibrations are transmitted to the coil in amplified ratio.

7. An electric phonograph reproducer comprising a casing, a magnet mounted in said casing and having pole pieces arranged to provide an airgap, a vibratory lever pivoted near one end to said casing, the short outer arm of said lever constituting a needle holder, and the long arm of said lever extending toward said airgap, a freely movable coil mounted on the inner end of said long arm and arranged to vibrate in said airgap to cut the magnetic flux, so that variable currents are generated in the circuit of said coil in accordance with the vibrations of the needle in said holder, the arms of said lever being so proportioned in length that the needle vibrations are transmitted to the coil in amplified ratio, and non-acoustic resilient means for normally holding said coil in predetermined position relative to said pole pieces.

8. In an electric sound reproducer, a magnet provided with pole pieces arranged to form an annular airgap, a vibratory lever pivoted near one end thereof so as to provide a short arm and a long arm, acoustic means for mechanically vibrating the short arm, and a cylindrical coil mounted on said long arm so as to vibrate axially in said annular airgap.

9. An electric phonograph reproducer comprising a shallow casing having substantially parallel front and rear walls, a magnet mounted flatwise in said casing against one of said walls and having pole pieces arranged to provide an airgap near the upper portion of said casing, a needle arm pivoted near one end to the lower por-

tion of said casing diametrically opposite said airgap, the longer section of said arm extending toward the magnetic pole pieces, a coil mounted on the free inner end of said 5 arm to vibrate across said airgap, and adjustable means for normally holding said coil in predetermined relation to said airgap.

10. In an electric phonograph reproducer 10 having a casing, a lever pivoted to said casing and adapted to be actuated by a record needle, a pair of spring-pressed members mounted in said casing and arranged to bear yieldingly against opposite sides of said lever for normally holding the same in predetermined position, said members having rounded surfaces in contact with said lever, and electromagnetic mechanism operated by 15 said lever.

20. 11. In an electric phonograph reproducer

having a casing, a pivoted lever adapted to be actuated by the vibrations of a record needle, electric reproducing mechanism within said casing operated by said lever, and a pair of spring-pressed members arranged 25 within said casing to engage said lever at opposite sides in the plane of its vibrations for normally holding the lever in predetermined position.

12. In an electric phonograph reproducer, 30 a pivoted lever adapted to be actuated by the vibrations of a record needle, electric reproducing mechanism operated by said lever, a pair of spring-pressed balls arranged to engage said lever at opposite sides in the 35 plane of its vibrations for normally holding the lever in predetermined position, and means to adjust the normal pressure of each ball against said lever.

ADOLPH A. THOMAS.
